United States Patent Office.

GEORG BERGNER, OF WASHINGTON, MISSOURI.

Letters Patent No. 91,510, dated June 22, 1869.

IMPROVEMENT IN VELOCIPEDES.

The Schedule referred to in these Letters Patent and making part of the same.

To all whom it may concern:

Be it known that I, GEORG BERGNER, of Washington, Franklin county, State of Missouri, have invented a new and useful improved Velocipede, of which the following is a full, clear, and exact description, reference being had to the annexed drawing, making a part of this specification, in which—

Figure 1 represents a side view of my invention, with a portion broken out.

Figure 2 represents a top view of same, also with a portion broken out.

Similar letters indicate like parts.

It consists of two concentric wheels, A B, fig. 1, A, fig. 2, the outer one having a broad tread, while the inner one is somewhat narrower.

In the periphery of B are placed friction-wheels a a' a'' , fig. 1, a , fig. 2, having central flanges, as seen at z , fig. 2, running in the channel v , fig. 1, cut in the rim of A.

This channel is cut deep enough to admit a series of cogs, 1, 2, 3, &c., below and out of reach of the flange of the friction-wheels.

Across the centre of B is placed a frame, D, its extremities fixed in the rim of B, one being forked, as seen in fig. 2.

These forks serve as bearings for a double spur-wheel, E, fig. 1, E E', fig. 2, and for a single spur-wheel, F, figs. 1, 2, which is made broad, and occupies the space between E E'.

On this wheel are two pinions o o' , fig. 2, o , fig. 1, one on either side, gearing with E E', while F engages with the cogs in the rim of A.

Two cranks, m m' , fig. 2, m , fig. 1, are attached to the shaft n , fig. 2.

These several wheels are so arranged as to leave room for the saddle, or seat H in the centre of the wheel and midway between the extremities of D, the front of the saddle s being made to curve over E E', so as to protect the rider.

Two supports, t t' , fig. 2, t , fig. 1, are placed under the saddle, and are slotted at p p' , p only being shown in fig. 1, so as to receive the pivot of the stirrups k k' , fig. 2, k , fig. 1, made of sheet metal, curved at one end, as seen, and which are made adjustable in these slots by means of thumb-screws v v' , fig. 2.

A hood, G, of leather, or other suitable material,

stretched over a frame, as seen, is hinged above the seat, and by the cord x passing over a pulley in the rim of B, not shown, is raised or lowered at pleasure.

Around the outer wheel are placed two rubber tires, w w' , fig. 2, w , fig. 1.

To give an idea of the dimensions of the various parts, I would recommend that, for an inner wheel, six feet in diameter, the tread of the outer wheel should be three or four inches, the driving-wheels about twenty inches, the follower from sixteen to twenty, the pinions from four to six, and the friction-wheels six inches in diameter; but of course I do not limit myself to any of these dimensions, as they may be varied at pleasure.

The rider being in the saddle, and bending slightly, so as to throw the centre of gravity forward, can, by turning the cranks, easily start the machine, after which he can sit upright.

In going down hill he would of course lean back, and the stirrups swinging freely on their pivots, his seat will be as easy, and he can control the speed as advantageously as in any other position.

Should it rain, or the sun be too hot, the hood can be dropped by simply loosening the cord, and as easily folded up again when desired.

If necessary a rim of sheet-iron may be placed around the upper edge of A, so as to keep the dirt from the inside, and so, perhaps, interfere with the gearing.

To guide the machine, it is only necessary to incline the body to one side or the other, or if this should not be sufficient, the foot may be allowed to impinge on the ground.

I do not claim to be the inventor of the single-wheeled velocipede, for I am well aware that such have been in use heretofore; but

What I do claim as my invention, and desire to secure by Letters Patent, is—

A velocipede combining the wheels E, E', and F, pinions o o' , cogs 1, 2, 3, &c., adjustable stirrups k k' , concentric wheels A and B, provided with friction-rollers a a' a'' , and seat H, all constructed, arranged, and operated substantially as and for the purpose shown and specified.

GEORG BERGNER.
